UNITED STATES PATENT OFFICE.

WILLIAM F. ESTES, OF OZARK, MISSOURI.

WRENCH.

1,153,050.

Specification of Letters Patent.

Patented Sept. 7, 1915.

Application filed February 17, 1915. Serial No. 3,844.

To all whom it may concern:

Be it known that I, WILLIAM F. ESTES, a citizen of the United States, residing at Ozark, in the county of Christian and State of Missouri, have invented new and useful Improvements in Wrenches, of which the following is a specification.

The present invention relates to improvements in pipe wrenches, the object of the invention being to construct a wrench of this character which shall be simple, comparatively cheap and thoroughly effective in use.

Another object of the invention is to provide a wrench including a stationary jaw having a threaded shank, a movable jaw arranged upon the said shank, a handle having a threaded bore adapted to be screwed upon the shank and a resilient and removable connection between the handle and the movable jaw, whereby one end of the said movable jaw may be fulcrumed upon the handle and swung thereon to assume an angle with relation to the stationary jaw.

With the above and other objects in view, the improvement resides in the construction, combination and arrangement of parts set forth in the following specification and falling within the scope of the appended claim.

In the drawing: Figure 1 is a perspective view of a wrench constructed in accordance with the present invention, Fig. 2 is a central longitudinal sectional view through the adjustable handle and the movable jaw thereof, and Fig. 3 is a perspective view of the spring connection between the movable jaw and the adjustable handle.

Referring now to the drawings in detail, the numeral 1 designates the head of a stationary jaw, and 2 the shank which is arranged at a right angle to the head. This shank, for the major portion of its length has its opposite edges provided with threads 3.

The numeral 4 designates the movable jaw and 5 the right angular shank or body thereof. The body 5 is provided with a bore whereby the same is loosely arranged upon the shank of the stationary jaw, and the said bore at its end formed with the jaw 4

is of a greater area than at its opposite end, 50 so that the opposite longitudinal walls provided by the bore are beveled or inclined from the jaw end of the said body to the opposite ends thereof and the reduced end loosely engages the shank of the stationary 55 jaw.

The numeral 6 designates a handle which is provided with a threaded bore that engages the threads of the shank 2 of the stationary jaw. The handle at its inner end 60 is formed with annular boss or shoulder 7 which is adapted to contact with the arcuate shaped end of the body of the movable jaw so as to allow the movable jaws to accommodate a slight arcuate movement. 65

The numeral 8 designates a flat spring which is removably connected to, what may be termed, the underface of the body of the movable jaw through the medium of a screw 9. The spring has one of its ends contacting 70 with the offset jaw provided upon the body or shank of the movable jaw and its opposite end formed with an angular flange which is adapted to engage with the annular or circumferential shoulder 7 of the handle. The 75 spring is adapted to exert a pressure so as to sustain the jaw of the movable member at an angle with relation to the jaw of the stationary member, but the cover 4 of the body of the movable jaw is so arranged that the 80 pressure of the spring will force the movable jaw normally into contact with an article arranged between the stationary and the movable jaws, as will be readily perceived by reference to the drawings. 85

From the above description, taken in connection with the accompanying drawing, the simplicity of the device, as well as the advantages thereof will, it is thought, be perfectly apparent to those skilled in the art to 90 which such inventions appertain without further detailed description.

Having thus described the invention, what I claim is:

In a wrench, a stationary jaw having its 95 shank provided at opposite edges with threads throughout the major portion of its length, a movable jaw having a tapering

bore, one wall of which normally lies parallel to one threaded edge of said stationary jaw, said movable jaw having an arcuate shaped extremity and a handle engaging the threads of the stationary jaw and having one end abutting the arcuate extremity of said movable jaw.

In testimony whereof I affix my signature in presence of two witnesses.

WILLIAM F. ESTES.

Witnesses:

F. W. BARRETT,
Tom R. MOORE.
